N. M. BARNES AND A. T. BARNES, OF TIFFIN, OHIO, ASSIGNORS TO THEMSELVES AND TIFFIN AGRICULTURAL WORKS, OF SAME PLACE.

Letters Patent No. 96,185, dated October 26, 1869.

IMPROVEMENT IN MACHINE FOR DRIVING RAKE-TEETH.

The Schedule referred to in these Letters Patent and making part of the same.

To all whom it may concern:

Be it known that we, N. M. BARNES and A. T. BARNES, of Tiffin, in the county of Seneca, and State of Ohio, have invented a new and improved Machine for Driving Rake-Teeth; and we do hereby declare that the following is a full, clear, and exact description of the construction and operation of the same, reference being had to the accompanying drawings, making a part of this specification, in which—

Figure 1 is a front elevation.

Figure 2 is a vertical section through line $z-z$ of fig. 1.

The object of this invention is to construct a simple and convenient machine for driving wooden-teeth into the heads of horse-rakes, that will perform the work more quickly, cheaply, and accurately, and with less danger of breaking or battering the teeth, than can be done by hand.

To this end, the machine consists of a supporting-frame, a crank placed upon a shaft, a rod connecting the crank with a cross-head working in guide-ways, a hammer attached to the cross-head for the purpose of driving the teeth, a rest to support the rake-head while the teeth are being driven, and a stop, operated by a spring or otherwise, to arrest and hold the tooth when it arrives at the proper point under the hammer, and directly in the line of its movement.

In the drawings—

A is the frame;

B is the shaft, supporting a driving-pulley, b, and a crank, C;

D is a rod connecting the crank to a cross-head, F, which runs on guide-ways, E E, and carries a heavy hammer, F', the face of which has a conical depression in it that fits over the end of the rake-tooth, when the hammer strikes the latter, and thereby prevents the tooth from being broken or battered by the heavy blows it receives;

G g, H h, are rests, which support and guide the rake-head, the body of the latter sliding between the lower end of the part g, and the upper edge of the part H, and the teeth resting against the front sides of the parts G H, (the one which the hammer is driving also resting against the front side of the part g, while the one opposite to it rests against the front side of the part h, beneath it;)

I is a broad standard in front of the rake-head, the under teeth passing behind it, and the head itself resting upon its upper edge, as shown in fig. 2; and

i i are two stops, with bevelled ends, actuated by a spring, J, or other equivalent device, in such a manner that they will yield to let a tooth pass in between them, as the rake-head is slid between the guides G H I, but, when the tooth gets between them, will thrust themselves out on each side of it, and hold

it immovable directly under the hammer, so that the latter, being put into operation by the rotation of shaft B, will rapidly and accurately drive the tooth into the rake-head.

The shaft B should be made strong enough to resist the pressure required, and may be driven by a pinion-gear, belt, and pulley, or any other suitable means. It should make about fourteen revolutions per minute. The supporting-frame should be made sufficiently strong and stiff not to spring while the machine is in operation.

The parts H h and I are made of the same height, the rake-head being supported upon them, and the lower teeth passing between them. The distance between the parts g H should be just sufficient to permit the head to slide easily. The machine may be used either in a horizontal or perpendicular position, but the latter is the most convenient, and requires less room.

The mode of operating the machine is as follows:

When the heads and teeth are all finished and ready to drive, the operator takes his place in front of the machine, so as to work the spring or lever with one hand, and assist in sliding the rake along with the other. One assistant then lays out the heads, and places the teeth in the holes, the whole length of the head, pushing them in as far as he can with his hand. Another assistant then takes the head and places it in line with the machine, the head resting upon the guide-rests, and moves it along so that the first tooth comes against the stop, directly under the socket in the hammer, when the latter, which is moving all the time, comes down and drives the tooth the length of the crank. As it rises, the next tooth is slipped in its place, and so on, and when the last tooth is reached, another assistant has placed another head in line, which follows the first, so that no stroke of the machine need be lost in changing from one head to another. Four men, with this machine, will drive from seven hundred to eight hundred teeth per hour, or seven thousand to eight thousand per day of ten hours.

The teeth may be driven as tight as is desired, or as tight as the timber will stand, and the machine will perform the same amount of work as though they were driven loose.

The advantages of this machine are—

First, ease of operation.

Secondly, rapidity, doing more work with four men, than could be done by twelve in the same time by hand.

Thirdly, accuracy, each tooth being driven just so far, and all in perfect line with each other, so that the points of the teeth, the whole length of the head, will be in line, instead of zigzag, as when driven by hand.

Fourthly, perfection and stability of work done.

The teeth may be driven so tight that no pin is needed to hold them in their places.

Fifthly, cheapness and simplicity. The machine can be made by any ordinary machinist, at a very small outlay.

What we claim, and desire to secure by Letters Patent, is—

1. The hammer F, provided with a socket in its face to fit the end of a rake-tooth, when used as and for the purpose set forth.

2. The combination of the guide-rests H and I, placed just far enough apart to permit the rake-teeth

to pass between them, substantially as and for the purpose specified.

3. The spring-plate J, combined with the lugs i i, and arranged and operating with respect to the rake-head, substantially as set forth.
